THOMAS HOUGHTON AND HENRY H. HOUGHTON, OF PHILADELPHIA, PENNSYLVANIA.

Letters Patent No. 97,922, dated December 14, 1869.

IMPROVEMENT IN FRUIT-JARS.

The Schedule referred to in these Letters Patent and making part of the same.

To all whom it may concern:

Be it known that we, THOMAS HOUGHTON and HENRY H. HOUGHTON, of the city and county of Philadelphia, and State of Pennsylvania, have invented a new and useful Improvement in Fruit-Jars; and we do hereby declare the following to be a full, clear, and exact description of the same, sufficient to enable others skilled in the art to which our invention appertains, to make and use the same, reference being had to the accompanying drawing, forming part of this specification, and illustrative of our invention.

Our invention consists in attaching a swinging bail to an endless band; which has a bearing below inclines on a shoulder formed on the body, or below the dome of the jar, so that when the cap or cover is placed on the neck of the jar, and the bail swung on said cap, a partial rotation of the band will tighten the bail and hold the cap firmly in position.

In the drawings—

A represents the body of a jar, which may be made of suitable form and material, and with a rounded bottom, *a*, and pedestals, B, as desired.

O represents the neck of the jar, which is of ordinary form and construction, and on it is placed a cap or cover D, which is likewise of ordinary construction, excepting that it may have a rounded top, and in the centre of which is a slight depression, *b*.

The upper part or dome L of the jar, is wider than the lower part, and overhangs it so as to leave an under shoulder, M, having inclines E, which are of form well known in the class of preserve-jars.

On the jar we slip an endless band, F, and provide an upward bearing for it against the lower sides of the inclines E.

G represents a bail, which is hinged at two points to the band F, and adapted to swing freely on its bearings.

The middle of the bail is bent downward to enter the depression *b* of cap D.

It is desirable that the upper edge of the band F should correspond with the inclines on shoulders E, so that the part *c* of the former should come against part *d* of the latter, and thereby form a stop to limit the rotation of the band in the direction of the arrow 1.

The operation is as follows:

The band F is slipped over the body of the jar from its bottom, and brought up against the shoulder M, with the parts *c* *d* in contact. Now swing up the bail G and place it on cap D.

A partial rotation of the band F, in direction of arrow 2, causes the band to slide downward, owing to the function of the inclines E, thereby drawing the bail G with it, and consequently tightening cap D.

It will be noticed that the central part of the bail G, during the rotation of the band, has a bearing in the depression of cap D.

The band can be rotated before or after the steam and hot air have escaped from the jar.

The cap D is permitted to arise when the parts *c* *d* are in contact, for then the bail G does not bear tightly against the cap.

When the cap or cover is tightened, the band bears firmly against the inclines, which, in return, are strong and durable, and prevent any slipping of the band.

All chipping and breaking are avoided, since the band and bail do not come in contact with the outer edges of the shoulder M.

When shoulders are blown on jars, they become at times quite thin, and the well known bail, hooking under the inclined planes, is apt to break said shoulders, but by the use of my endless band, the pressure is equally distributed on the shoulder M.

In the present case, the jar tapers from the shoulder M, or lower edge of dome, to its bottom, in order to readily admit the band.

The amount of pressure on the cap D is regulated by the degree of rotation of said band.

Having thus described our invention,

What we claim as new, and desire to secure by Letters Patent, is—

The band F, with bevelled or inclined edge, and the bail G hinged thereto, in combination with the overhanging dome L, having an inclined bearing-surface for said band, substantially as and for the purpose described.

To the above, we have signed our names, this 22d day of July, 1869.

THOMAS HOUGHTON.
HENRY H. HOUGHTON.
